(57) **CLAIM**

The ornamental design for a table, as shown and described.

DESCRIPTION

FIG. 1 is a top perspective view of a table;

FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The longer dashed broken lines depict portions of the table that form no part of the claimed design. The shorter dashed broken lines depict chain that form no part of the claimed design. The dot-dashed broken lines represent boundaries of the claimed table and form no part of the claimed design.
